UNITED STATES PATENT OFFICE.

NEWELL V. DYER, OF HOLBROOK, MASSACHUSETTS, ASSIGNOR TO UNITED SHOE MACHINERY CORPORATION, OF PATERSON, NEW JERSEY, A CORPORATION OF NEW JERSEY.

SKIVING MACHINE.

Application filed August 13, 1919. Serial No. 317,311.

To all whom it may concern:

Be it known that I, NEWELL V. DYER, a citizen of the United States, residing at Holbrook, in the county of Norfolk and State of Massachusetts, have invented certain Improvements in Skiving Machines, of which the following description, in connection with the accompanying drawings, is a specification, like reference characters on the drawings indicating like parts in the several figures.

This invention relates to skiving machines and is herein illustrated as embodied in a machine of the Amazeen type such as is shown in the patent to Bayley No. 823,578, granted June 19, 1906.

In the manufacture of certain kinds of boots and shoes it is desirable to produce two or more scarfs which shall be different in width or in character or in both. For example, it may be desirable to produce along the top and front of a quarter a shoulder scarf, to produce along the back a seam scarf, and to produce along the bottom a feather-edge scarf. Up to the advent of the machine of application Ser. No. 175,966, filed in my name on June 20, 1917, now Patent No. 1,327,028, it was necessary to adjust several parts of the machine to produce these different scarfs. In the machine of the application there is provided a feed roll having two work supporting surfaces to either of which the work may be guided at will by a work gaging member similar to that shown in Patent No. 1,138,645, granted to me on May 11, 1915. Two different scarfs may be produced with the work supported upon one surface by causing the work to be guided differently on said surface, while a

third scarf may be produced when the work is guided on the second surface, the feed roll being adjustable toward and from the knife to bring one or the other surface into proper position. This machine has been put into use in considerable numbers and found satisfactory except in certain factories in which a long feather-edge scarf is desired. The length possible to impart to a scarf of this character depends upon the width of one of the surfaces on the feed roll; and for reasons which have to do with the proper relation of the cutting edge of the knife to the roll it

is not desirable to make this surface very wide.

According to one feature of the invention the roll is provided with a single work-engaging surface and is made adjustable in such manner that all of the different characters of scarfs may be produced while the work is supported on this surface. In the illustrative machine the feed roll is mounted in an angularly adjustable carrier, the axis about which the carrier is adjustable extending at right angles to the axis of the roll and being tangential to the roll at a point spaced from the ends thereof. Normally the roll occupies a position with respect to the knife such that a shoulder scarf will be produced, and when the roll is adjusted about the axis referred to a feather-edge scarf will be produced the length of which is substantially the same as that of the shoulder scarf instead of being shorter than that of the shoulder scarf as in the machine of the application.

It is desirable for reasons which will appear later that the roll carrier be locked in some of its positions, and another feature of the invention relates to such locking means and to the means for releasing and adjusting the roll carrier. In the illustrative machine a treadle controlled member may be manipulated to perform both the release and the adjustment.

These and other features of the invention will be described as embodied in an illustrative machine and pointed out in the appended claims.

Referring now to the accompanying drawings,

Fig. 1 is a front elevation of a portion of a skiving machine in which the present invention is embodied;

Fig. 2 is a rear elevation of the tilting carrier for the feed roll shaft;

Fig. 3 is a rear elevation showing the tilting carrier, the carrier guide and the feed roll;

Fig. 4 is an elevation of the same parts as are shown in Fig. 3 but showing the roll carrier and roll tilted;

Fig. 5 is a fragmentary plan showing more particularly the mechanism for locking the tilting carrier; and

Fig. 6 comprises three sectional views of three scarfs of different types.

The illustrative machine is of the well known Amazeen type, in which the work is fed to a rotary disk knife by means of a feed roll and a feed disk. Except for the roll and gage mechanism and their associated parts, the machine is or may be substantially like that shown in the patent to Bayley. A portion of the rotary disk knife is indicated at 7 and a portion of the feed disk at 9, these parts being constructed, mounted and driven as in the patented machine, to which reference is made for a detailed description. It will be understood that the feed disk 9 is urged downward continually by a spring so that it will follow the roll in its tilting movement.

Referring first to Fig. 6, there are shown in section three different types or characters of scarfs. At 100 is shown a shoulder scarf, at 200 a feather-edge scarf, and at 300 a seam scarf. The two latter being straight scarfs as distinguished from the shoulder scarf. With the machine of my prior application it was possible to produce three scarfs of these general types without adjustment of the knife or edge gage by reason of the provision, among other elements, of a special roll having two surfaces upon either of which the margin of the work could be supported while being skived. A shoulder scarf or a seam scarf could be produced at will while the work was supported on one surface; and when a feather edge scarf was desired, the other surface was made use of. In the present machine all three types of scarf may be produced, one after the other, while the margin of the work is supported on one and the same surface of the roll, two of the scarfs, the feather-edge scarf and the seam scarf being produced while the roll is in one position, and the other, the shoulder scarf, being produced while the roll is in another position.

Referring now to the remaining figures, the base 11 of the machine has pivoted to it at 13 a bracket 15, said bracket being adjustable about the pivot by a screw 17 and being held in adjusted position by a screw 19, this construction being substantially like that shown in the Bayley patent, its purpose being to permit adjustment of the feed roll toward and from the knife. Mounted in this bracket is a shaft 21 which corresponds to the feed roll shaft of the Bayley patent, and like that shaft is driven by means of bevel gears 23, 25. The forward end of the shaft 21 has a socket in which is fastened by a pin 27 the rear rounded end of a link 29, the forward rounded end of the same link being fastened by a pin 31 in a socket in a member 33. The pins 27 and 31 pass through the usual slots in the rounded ends of the link 29 so that the shaft 21 and the member 33

are connected by a universal joint. A feed roll 35 is fast at the outer end of a shaft 37 which passes through a bearing in a roll carrier 39 and into a socket in the member 33, the shaft being adjustably fastened to the member by set screws, one of which is shown at 41. The roll carrier 39 is provided with a segmental rib 43, which fits in a segmental groove 45 in the bracket 15, and is held in place by a plate 46 and screws 47 which pass through the plate and into threaded holes 49 in the rib 43. The segmental groove is struck about an axis which is at right angles to the axis of rotation of the roll and is substantially tangential to the periphery of the roll at a point 51 which is spaced from the ends of the roll. Consequently, when the roll carrier 39 is tilted, the roll is adjusted angularly about that axis, as indicated in Fig. 4, the inner end of the roll being raised and the outer end lowered. In order to permit the position of this axis to be changed with respect to the roll, a plurality of washers 53 are located between the inner end of the roll and the outer end of the roll carrier 39. When one of these washers has been removed the roll and its shaft may be adjusted inwardly (to the right in Fig. 1 or to the left in Figs. 3 and 4) with the result that tilting the roll carrier a given extent will raise the inner end of the roll to a higher level than would have occurred had the roll occupied the position with respect to the carrier shown in the drawings. The roll comprises a frusto-conical nurled portion 135, which terminates at its outer end in a shoulder, and a smooth portion 235. The nurled portion is the operative work-engaging surface for supporting the margin of the work which is being skived. The smooth portion merely co-operates with the feed disk 9 to advance the work. No skiving is done upon that portion of the work supported thereby. The roll, therefore, has a single work-engaging surface which is adapted to permit skiving of the work upon it.

The roll carrier 39 is normally held in the position shown in Figs. 1 and 3 by a spring 55, the free end of which engages a pin 57 driven into the plate 46, a portion of the spring being coiled about a pin 59 driven into the bracket 15, and having its other end located in a recess 61 in the bracket 15, further downward movement of the roll carrier being prevented by contact of the bottom surface of the carrier with the adjacent upper surface of the bracket. With the roll carrier in this position, the element of the nurled surface 135 of the roll which is adjacent to the knife is substantially parallel to the plane of the knife so that a shoulder scarf will be produced.

The roll carrier 39 is normally locked in its horizontal position by means of a block 63 and a crank pin 65. The block is located

in a horseshoe-shaped recess in the segmental guide rib 43 and has an operative face 163 which is curved to correspond to the curve of the edge of the guide. This face is 5 is in contact with the adjacent face of the curved guide slot 45 so that when the block is forced outwardly (to the right as viewed in Figs. 2, 3, 4 and 5) the carrier is locked in position. The crank pin 65 is an eccentrically 10 located, reduced portion of a stud 67 which is capable of oscillation in alined bearings formed respectively in the plate 46 and in the roll-carrier 39, said plate being in effect part of the carrier. On that end of the 15 stud 67 which projects from the plate is fastened one end of a crank 69, the other end being pivoted at 71 to the upper end of a treadle rod 73. This rod is pivoted at its lower end of a treadle (not shown) of such 20 construction that manipulating the treadle raises the rod and freeing the treadle allows the rod to descend.

The operation of tilting or angularly adjusting the roll carrier takes place as follows:—The parts are normally in the positions best shown in Figs. 2 and 3 with the roll carrier 39 in its horizontal position and locked in place by the action of the block 63. When it is desired to tilt the roll carrier, and with it the roll, the treadle is manipulated to raise the treadle rod. The first effect of this upward movement is to unlock or release the carrier, which takes place before the upper end of the treadle rod contacts with the pin 57. Thereafter the rod by pushing upwardly against the pin, tilts the roll about the axis 51 until an adjustable stop in the form of a nurled nut 75 threaded on the treadle rod 73 contacts with the frame 30 of the machine. The operator holds the roll in this position (see Fig. 4) until the particular scarf desired has been produced on the work and then releases the treadle. The spring 55 is strong enough to hold the pin 57 40 against the upper end of the rod 73 while it is returning the roll carrier to horizontal position. After the roll carrier has reached this position and stopped, the treadle continues its downward movement, thereby rotating the stud 67 and locking the carrier, the final and normal position of parts being shown best in Fig. 3. Ordinarily the adjustment of the roll will be carried out as has been described, but it should be noted that the roll 50 carrier may be locked in any angular position by tilting the carrier to the desired position, holding the carrier for a moment with the hand and then releasing the treadle. Thereafter the angular position of the roll and roll carrier will be maintained until the treadle is again manipulated. The purpose of providing the locking mechanism is first to ensure that the roll shall not vibrate when in its normal, horizontal position, and second 60 to provide for holding it similarly in any de-

sired angular position. The lock is not necessary and has not been made normally operative for that position, as in Fig. 4, in which the treadle is being held down firmly by the operator.

Referring now to the work gaging or guiding device, this is or may be substantially the same as shown and described in my prior application and will therefore be described only in a general way. The presser foot 77 and edge gage 79 are rigid with each other and held in position by a thumb screw 81. After the thumb screw has been loosened, the foot and gage may be adjusted longitudinally of the roll to provide for 75 scars of different widths. Although the gage 79 may thus be adjusted, it will be referred to as the stationary gage to distinguish it from the movable gage 83, the stem of this latter gage being pivoted at 85 to a member which may be adjusted along the roll by turning the thumb-nut 87. The movable gage is thus adapted to permit the work to be introduced beneath it so as to be guided by the stationary gage 79 or to permit the edge of the work to be held against it, in which case it performs the guiding function. The gages may be adjusted in unison along the roll or may be adjusted 80 separately to vary the distance between them, and either gage may be used at any time.

Assuming that the parts of the machine are in the positions shown in Fig. 1, the operation of the machine to produce the scars indicated at 100, 200 and 300 is as follows. The work is introduced beneath the movable gage 83 with its edge against the stationary gage 79 and fed through the machine to produce the shoulder scarf 100. If it is desired to produce the feather-edge scarf 200, the roll 100 is first tilted to the position shown in Fig. 4, and the work is then presented in the same manner as indicated above, being guided by the stationary gage 79. It will be noted that the feather-edge scarf thus produced is 105 of substantially the same length as that of the shoulder scarf. If it is desired to produce the seam scarf 300, the roll is tilted as for the feather-edge scarf but the gage 83 is used to guide the work.

By reason of the fact that the axis about which the roll is tilted is substantially tangential to the periphery of the roll at a locality spaced from the ends thereof, it will be noted that the tilting of the roll simultaneously raises the inner end of the roll and lowers the outer end. It is the raising of the inner end into the plane of the cut of the knife which causes the feather-edge scarf to be produced; and the point 51 should therefore be spaced a substantial distance from the inner end of the roll. In practice a spacing from the inner end of the roll of from one thirty-second to three-sixteenths of an 115 inch has adapted the machine to produce 120 125 130

satisfactorily the usual scarf's on the usual thicknesses of work; but it should be understood that these definite figures are given by way of explanation; and not of limitation.

5 Although the invention has been set forth as embodied in a particular machine, it should be understood that the invention is not limited in the scope of its application 10 to the particular machine which has been shown and described.

Having thus described my invention, what I claim as new and desire to secure by Letters Patent of the United States is:

15 1. A machine of the class described having, in combination, a feed roll having a single work-engaging surface adapted to permit skiving of work upon it, and work gaging means for guiding the work over 20 the roll in either of two different positions to produce either a feather-edge or a seam scarf; said roll being adjustable to produce a shoulder scarf.

25 2. A machine of the class described having, in combination, a skiving knife, a feed roll for advancing work to the knife, and an angularly adjustable member by which the roll is carried, the axis about which the member is adjustable being substantially 30 tangential to the periphery of the roll at a point spaced from the ends thereof.

35 3. A machine of the class described having, in combination, a skiving knife, a feed roll for advancing work to the knife, and an angularly adjustable member by which the roll is carried, the axis about which the member is adjustable being substantially tangential to the periphery of the roll at a point spaced from the ends thereof, 40 the roll being adjustable in its adjustable carrier in a direction transverse to the direction of feed of the work to vary the location of said axis with respect to the ends of the roll.

45 4. A machine of the class described having, in combination, a skiving knife, a feed roll having a working surface terminating in a shoulder, said roll being normally so located with respect to the knife that the 50 element of its working face nearest to the plane of the knife is substantially parallel to said plane so that a shoulder scarf will be produced, and means for permitting the roll to be adjusted about an axis which is substantially at right angles to the element and passes through it at a point spaced from the ends to cause a straight scarf to be produced.

55 5. A machine of the class described having, in combination, a skiving knife, a feed roll having a working surface terminating in a shoulder, said roll being normally so located with respect to the knife that the element of its working face nearest to the 60 plane of the knife is substantially parallel

to said plane so that a shoulder scarf will be produced, and means for permitting the roll to be adjusted about an axis which is substantially at right angles to the element and passes through it at a point spaced 70 from the ends to cause a straight scarf to be produced, the mounting of the roll being such that it may be adjusted in the direction of its length to vary with respect to the roll the location of the axis about which 75 it is adjustable.

6. A machine of the class described having, in combination, a skiving knife, a rotary feed roll, and means for tilting the roll in such manner as simultaneously to 80 lower one end of the roll and raise the other end into the plane of the cut of the knife, the mounting of the roll being such that it may be adjusted to vary the relative extent of the raising and lowering of the two 85 ends.

7. A machine of the class described having, in combination, a feed roll, a skiving knife the plane of the cut of which is normally substantially parallel to the adjacent 90 element of the surface of the feed roll, and means whereby the roll may be tilted to cause the element to be intersected by the plane, the mounting of the roll being such that it may be adjusted to vary the point 95 of intersection.

8. A machine of the class described having, in combination, a rotary disk skiving knife, a feed roll for advancing work to the knife, and an angularly adjustable member 100 by which the roll is carried, the axis about which the member is adjustable being substantially tangential to the periphery of the roll at a point spaced from the ends thereof.

9. A machine of the class described having, in combination, a skiving knife, a feed roll for advancing work to the knife, means for holding the roll in position to produce with the knife a shoulder scarf, and operator controlled means adapted to be manipulated during the operation of the machine 105 for tilting the roll about an axis which is substantially tangential to the periphery of the roll to produce a straight scarf.

10. A machine of the class described having, in combination, a skiving knife, a feed roll for advancing work to the knife, means for normally holding the roll in position to produce with the knife a given scarf, and treadle-controlled means for tilting the roll about an axis which is substantially tangential to the periphery of the roll to vary the character of the scarf produced.

11. A machine of the class described having, in combination, a skiving knife, a feed roll having a single work-supporting surface adapted to permit skiving of work upon it, means for normally holding the knife and roll in relative positions to produce a given scarf, and treadle controlled means 125 130

for varying the relative positions of the knife and roll to produce a different scarf.

12. A machine of the class described having, in combination, a skiving knife, a feed roll having a single work supporting surface adapted to permit skiving of work upon it, means for normally holding the knife and roll in relative positions to produce a given scarf, and treadle controlled means for tilting the roll so as to support the work differently with respect to the knife to vary the character of the scarf produced.

13. A machine of the class described having, in combination, a skiving knife, a feed roll having a single work supporting surface adapted to permit skiving of work upon it, means for normally holding the knife and roll in relative positions to produce a given scarf, and treadle controlled means for tilting the roll about an axis substantially tangential to the roll at a point spaced from the ends thereof.

14. A machine of the class described having, in combination, a skiving knife, a feed roll for advancing the work to the knife, work gaging means having a member beneath which the work may be introduced or against which it may be held, and means for adjusting the roll about an axis which is substantially tangential to the roll at a point spaced from the ends thereof.

15. A machine of the class described having, in combination, a skiving knife, a feed roll for advancing the work to the knife, work gaging means having a member beneath which the work may be introduced or against which it may be held, and treadle controlled means for adjusting the roll about an axis which is substantially tangential to the roll.

16. A machine of the class described having, in combination, a skiving knife, a feed roll having a single work supporting surface adapted to permit skiving the work upon it, said roll being normally held in position to cause the knife to produce a shoulder scarf; work gaging means having a member beneath which the work may be introduced or against which it may be held, and means for adjusting the roll angularly to cause the knife to produce a straight scarf.

17. A machine of the class described having, in combination, a skiving knife, a feed roll for advancing work to the knife, an adjustable carrier for the roll, means for normally locking the carrier in one position, and a member manipulation of which first unlocks the carrier and then changes its adjustment.

18. A machine of the class described having, in combination, a skiving knife, a feed roll for advancing work to the knife, an angularly adjustable carrier for the roll, means for normally locking the carrier in one posi-

tion, and a member manipulation of which first unlocks the carrier and then changes its adjustment.

19. A machine of the class described having, in combination, a skiving knife, a feed roll for advancing work to the knife, an adjustable carrier for the roll, means for normally locking the carrier in one position, and treadle controlled means for releasing the carrier.

20. A machine of the class described having, in combination, a skiving knife, a feed roll for advancing work to the knife, an angularly adjustable carrier for the roll, means for normally locking the carrier in one position, and treadle controlled means for releasing the carrier.

21. A machine of the class described having, in combination, a skiving knife, a feed roll for advancing work to the knife, an adjustable carrier for the roll, means for normally locking the carrier in one position, and a member movement of which in one direction releases the carrier and changes its adjustment and in another direction permits return of the carrier to the first position and locks it.

22. A machine of the class described having, in combination, a skiving knife, a feed roll for advancing work to the knife, an angularly adjustable carrier for the roll, means for normally locking the carrier in one position, and a member movement of which in one direction releases the carrier and changes its adjustment and in another direction permits return of the carrier to the first position and locks it.

23. A machine of the class described having, in combination, a skiving knife, a feed roll for advancing work to the knife, a carrier for the roll adjustable about an axis which is substantially tangential to the periphery of the roll, means for locking the carrier in a selected position, and treadle controlled means for releasing the carrier.

24. A machine of the class described having, in combination, a skiving knife, a feed roll for advancing work to the knife, a carrier for the roll adjustable about an axis which is substantially tangential to the periphery of the roll, means tending at all times to move the carrier to and hold it in a given position, and means for moving the carrier in opposition to said first-named means.

25. A machine of the class described, having in combination, a skiving knife, a feed roll for advancing work to the knife, and an angularly adjustable member by which the roll is carried, the axis about which the member is adjustable being tangential to the periphery of the roll on the same side of the roll as that on which the knife is located and at a locality near one end of the roll but spaced from the end.

26. A machine of the class described having, in combination, a skiving knife, a feed roll for advancing work to the knife, an angularly adjustable carrier by which the roll is carried, the axis about which the member is adjustable being substantially tangential to the periphery of the roll at a point spaced a substantial distance from one end thereof,

and means whereby the roll and knife may be adjusted relatively to each other in a direction transverse to the direction of feed of the work. 10

In testimony whereof I have signed my name to this specification.

NEWELL V. DYER.
